UNITED STATES PATENT OFFICE.

GEORGE B. HOLLAND, OF NAUGATUCK, CONNECTICUT.

WINDOW-SHADE FIXTURE.

1,422,056.

Specification of Letters Patent. Patented July 4, 1922.

Application filed July 25, 1921. Serial No. 487,493.

To all whom it may concern:

Be it known that I, GEORGE B. HOLLAND, a citizen of the United States, and a resident of Naugatuck, county of New Haven, and State of Connecticut, have invented certain new and useful Improvements in Window-Shade Fixtures, of which the following is a specification.

This invention relates to shade and curtain fixtures for the windows of a dwelling house and one object is to produce a combination bracket to be used to support the usual shade-roller, curtain rod and overdrapery-rod.

Another object is to provide a window-shade fixture or window-bracket of this nature, which may be cheaply constructed from a single piece of sheet metal, as by stamping and bending, and without the use of complicated tools or machinery.

A further object is to provide an improved window-bracket of this class which can be quickly and easily put up and taken down without the use of a high degree of skill, and with the minimum of injury to the wood-work of the window easing.

A still further object is to provide a window-bracket, which will be strong, durable, and attractive in use, and which when out of use, will occupy only a small space.

With these and other objects in view, there is illustrated in the accompanying drawings, one form in which the invention may be embodied in practice.

In the drawings, Figure 1 is a top view, with parts broken away, showing two of the window-brackets in position—attached to the window casing—and holding a shade-roller, curtain-rod, and overdrapery-rod in their operative relation.

Figure 2 is a perspective view showing the appearance of the window fixtures when in use, with a shade, a curtain, and overdraperies, hanging therefrom.

Figure 3 is a plan view of the stamped metal blank, from which the right-hand bracket is later bent into shape.

Figure 4 is a similar view of the stamped metal blank, from which the left-hand bracket is later formed.

Figure 5 is a perspective view of the left-hand bracket.

In the drawings, in which similar reference characters denote corresponding parts throughout the several views,

The numeral 10 represents the window cas-

ing within which the window 11 is adapted to slide up and down in the usual manner.

The right-hand combination bracket 12, and the similar left-hand bracket 13, are secured to the corresponding sides of the window casing 10 by nails or screws 14, two of which nails or screws, are required for each bracket, and are disposed vertically over one another. These nails or screws pass through the holes 14^a, in the brackets.

These brackets 12 and 13 may be constructed from various materials, but it is preferred to stamp them out of sheet brass or tin, the thickness of the sheet being sufficient to give the necessary rigidity and strength to the finished brackets.

Each of the brackets 12 and 13, consists of an intermediate attaching plate 15, and is provided with upstanding arms 16 and 17 respectively. These arms are bent at right angles to the plate 15 and are parallel to one another. The inner arm 16, of the bracket which is much shorter than the outer arm 17, constitutes a support or a journal for the end of the shade roller 23. In the right-hand bracket 12, the inner arm 16 is provided with a circular socket or eyelet 18, to receive the cylindrical pintle 19 of the shade roller 23. On the left-hand bracket 13, however, the inner arm 16 is provided with a V-shaped recess, having the two portions 20 and 21 of the V arranged at an obtuse angle to one another, as clearly shown in Figure 4. In use, this V-shaped recess, receives the flat gudgeon or rectangular pintle 22 of the spring-actuated end of the shade roller 23, which carries the shade 24 wound spirally upon it, as clearly shown in Figure 1.

The longer and outer arm 17 of each bracket, is provided with a circular socket or eyelet 25 at about its mid-point, to receive the ends of the curtain rod 28. This rod 28 is preferably made hollow, and its ends are secured in position within the eyelets 25 by removable knobs 26, which are preferably spherical, as shown, and have portions 27, adapted to fit within the hollow curtain-rod 28.

A U-shaped overdrapery-rod 29 is also employed, being secured in position by fitting its hollow ends 30 over the flat tapered extremities 31 of the brackets 12 and 13. The angle of these tapered extremities 31 is such that when in use they fit tightly in the ends 30 of the rod 29, so as to grip the latter and prevent it from accidentally working loose.

The form of the blank after being stamped and before bending into its final shape is clearly shown in Figures 3 and 4, and it will be noted that it contains a minimum amount of material and also presents an ornamental appearance.

Surrounding the shade-roller eyelet 18, the end of the arm 16 is made semicircular and tapers inwardly therefrom to the junction 10 of the attaching plate 15, the latter being provided with pointed, V-shaped tips 32, arranged vertically above and below the symmetrically placed nail or screw holes 14^a. To further heighten the ornamental appearance, as well as to economize in metal, the outer arm of the bracket is provided with an oval-shaped portion 33, which immediately adjoins the attaching plate 15, and is perforated by the holes 34 as shown. Beyond 20 the oval-shaped portion 33, the curtain-rod socket or eyelet 25, is surrounded by the circular portion 35 which connects with the straight tapering overdrapery-rod supporting section 31, the latter being terminated 25 by the curved tip end 36.

When it is desired to use the brackets, they are first nailed or screwed in position on both sides of the casing 10, as shown in Figures 1 and 2. The shade 24, the shirred 30 curtain 37 and the overdraperies 38, 39, and 40 are then arranged upon the shade-roller, curtain-rod, and overdrapery-rod respectively—the latter then being readily inserted in the brackets 12 and 13. The removable knobs 26 are next fitted within the ends of the curtain-rods 28. The parts are now completely assembled.

It will be evident from the foregoing description that the use of brackets constructed in accordance with the present invention will cause the window coverings to hang evenly and uniformly. This is due to the fact that the shade-roller, curtain-rod and overdrapery-rod are suspended from 45 two supports instead of six as in the usual hanging fixtures for the windows of a dwelling house.

It will also be apparent—considering one side of the window casing only—that the devices usually found in three separate supports, have been combined into a single unitary bracket, which may be put up or taken down in about one third of the time formerly required. This, of course, eliminates 55 the excessive number of attaching screws employed with the usual form of hanging fixtures, and thereby undue injury to the woodwork of the casing is avoided. Moreover, when the parts are in their operative 60 relation, it will be noted that the entire structure forms a rigid frame-work, which includes the right-hand and left-hand brackets, the shade-roller, the curtain-rod, and the overdrapery-rod.

65 This frame-work remains rigid even after

the brackets have been detached from the window casing, and hence the shade, curtain, and overdraperies may be taken down "en bloc", for cleaning and dusting, without separating them from the brackets. 70

While the curtain-rod and overdrapery-rod are preferably made from hollow tubing, as illustrated herein, the invention in its broad aspects is not limited to such constructions, but covers the use of solid or 75 partly solid rods, as well. Moreover, the invention broadly covers a window-bracket having a hollow or a conical end instead of the flat-tapered extremity 31 of the arm, as illustrated. 80

While there has been disclosed in this specification, one preferred form in which this invention may be embodied, it is understood that this form is shown for the purpose of illustration only, and that the 85 invention is not to be limited to this specific disclosure, but the invention may be modified and embodied in various other forms without departing from its spirit; in short, the invention includes all the modifications coming within the scope of the following claims. 90

Having thus fully described the invention, what is claimed as new, and for which it is desired to secure Letters Patent, is: 95

1. A combination bracket for supporting a shade-roller, a curtain-rod, and an overdrapery-rod, said bracket comprising a U-shaped member, having two arms and a base, one of said arms having an opening 100 for receiving the pintle of a shade-roller, and the other arm having an opening to receive the end of a curtain-rod, said last named arm also having a tapered extension adapted to fit within the hollow end of an 105 overdrapery-rod, said bracket also having an intermediate section provided with screw or nail holes for attachment to the casing of a window.

2. A combination bracket for supporting a shade-roller, a curtain-rod, and an overdrapery-rod, said bracket comprising a U-shaped member, having two flat parallel arms and a base, one of said arms having an opening for the pintle of a shade-roller, and the other arm having an opening to receive the end of a curtain-rod, said last named arm also having a portion adapted to fit within the hollow end of an overdrapery-rod. 110 115

3. A bracket for window fixtures, comprising, in combination, a shade-roller supporting section and a curtain-rod and overdrapery-rod supporting section, said last named section having a tapered extremity 125 of ornamental appearance adapted to fit into the hollow end of an overdrapery-rod.

4. A bracket for window fixtures stamped from a single strip of thin sheet metal and comprising in combination a base, an arm 130

for supporting one end of a shade roller and a second arm having a flat tapered extremity with straight edges for supporting one end of a U-shaped tubular drapery rod.

5. In a sheet metal bracket for window fixtures, an arm for supporting a tubular overdrapery-rod, said arm having an open-

ing for receiving the end of a curtain rod and an integral tapered portion beyond said opening adapted to fit into said tubular 10 overdrapery-rod.

In testimony whereof, I have affixed my signature to this specification.

GEORGE B. HOLLAND.
